UNITED STATES PATENT OFFICE.

HUMPHREY EVANS, OF MILWAUKEE, WISCONSIN, ASSIGNOR TO HOLEPROOF HOSIERY CO., OF MILWAUKEE, WISCONSIN, A CORPORATION OF WISCONSIN.

OVERSTITCH SEWING-MACHINE.

1,262,762.

Specification of Letters Patent. Patented Apr. 16, 1918.

Application filed April 26, 1917. Serial No. 164,617.

To all whom it may concern:

Be it known that I, HUMPHREY EVANS, a citizen of the United States, residing at Milwaukee, in the county of Milwaukee and 5 State of Wisconsin, have invented certain new and useful Improvements in Overstitch Sewing-Machines, of which the following is a specification, reference being had to the accompanying drawing, forming a part 10 thereof.

This invention relates more particularly to means for holding and feeding the work to the stitching mechanism, means for trimming raw or unfinished edges of the fabric 15 after it is secured in place and before it is overstitched, and means for severing the chain or bonds between adjoining sections or pieces of work, and to the arrangement of the holding and feeding means relative 20 to the stitching mechanism.

Its main objects are to feed one piece of work after another to the stitching mechanism without interruption; to facilitate placing and securing the work in proper position on the work holder and carrier; to avoid soiling the work; and generally to improve the construction and operation of machines of the class to which the invention pertains.

30 It consists in the construction, arrangement and combination of parts as herein-after particularly described and pointed out in the claims.

In the accompanying drawing, showing a 35 machine embodying the invention and specially designed for sewing reinforcements on glove fingers, like characters designate the same parts in the several figures.

Figure 1 is a plan view of the machine, 40 the cover plate over parts of the stitching mechanism being removed; Fig. 2 is a vertical section on the line 2—2, Fig. 1, and side elevation of the machine; Fig. 3 is a vertical section on the line 3—3, Fig. 1, showing 45 means for manually turning the work carrier either backward or forward; Figs. 4 to 8 inclusive, are detail views on an enlarged scale, showing a portion of the work carrier in section, and a part of one of the work 50 holding clamps, and illustrating the trimming, stitching, chain cutting, work releasing and work stripping operations of the machine; Fig. 9 is a vertical section on the line 9—9, Fig. 1, showing the clamp opening device and the stripping device; Fig. 10

is a view similar to Fig. 4 showing the edge lifter in relation to the chaining point; and Fig. 11 is a side elevation of the edge lifter and chaining point in connection with a portion of the work carrier and clamps, as 60 viewed from the right relative to Figs. 1, 2 and 10.

The machine comprises a base 1, adapted to be screwed or otherwise attached to and supported on a table or shelf 2, as shown in 65 Figs. 1 and 2. On the front side overhanging the table or shelf 2, the base 1 is formed with a grooved ring 3. On this ring is rotatably mounted an annular or cylindrical work support and carrier 4, formed on its 70 lower side or end with a tongue 5, freely fitting the groove in the ring 3 and confined therein by a split or sectional retaining ring 6. Just above the ring 6 the carrier 4 is formed or provided on the outside with a 75 gear or rack 7, with which a pinion 8 meshes on the rear side of the carrier. A ratchet wheel 9, attached to the upper side of the pinion 8, is mounted on a stud 10, fastened in and projecting upwardly from the 80 ring 3. The work support and carrier 4 is intermittently turned to feed the work to the stitching mechanism step by step, as hereinafter explained, by a pawl 11, pivoted on an arm 12 of a vertical rocker shaft 13, 85 and held in yielding engagement with the ratchet wheel by a spring 14. The shaft 13 is provided with an arm 15, having a roller at its free end held by a spring 16 in engagement with a crown cam 17 on a horizontal shaft 18, which also serves to actuate 90 the trimmer, stitching mechanism and chain cutter, as hereinafter explained.

The stitching mechanism, which may be like or similar to that used in overstitch 95 sewing machines, comprises a horizontal reciprocating needle bar 19, supported in bearings in a case 20, above and transversely to the cam shaft 18, and extending therefrom transversely over the rear side of 100 the work support and carrier 4. At its front end the bar 19 is provided with a head 21, on which a vertically adjustable slide 22 is guided. To the lower end of the slide 22 the shank of a holder 23 for a needle 24, is 105 adjustably clamped. The slide 22, with the holder 23 and a needle 24, is adjusted vertically by a screw 25, and is secured in adjusted position by a screw 26. The needle is operated by a cam 27, mounted on the shaft 110

18 and engaging a forked head 28 on the bar 19.

A looper 29, coöperating with the needle 24 to form an overstitch seam, is carried by 5 a lever 30 pivotally mounted on a rocker arm 31, which is actuated by a cam 32 on the shaft 18, to shift the looper forward and backward across the work held on the support and carrier 4. An offset of the rocker 10 arm 31 is held in engagement with the cam 32 by a spring 33. The lever 30 is actuated by cams 34 and 35, with which it is held in engagement by a spring 36, to impart up and down and lateral movements to the 15 looper 29 in properly timed relation to the movements of the needle 24.

So far as the present invention is concerned, stitching mechanism designed to use one or two threads, may be used. In the 20 present case, single thread stitching mechanism is illustrated, and the thread therefor is carried, as shown in Fig. 2, around a tension 37 and over a take-up 38 mounted on a removable cover 39 of the case 20, which is provided with bearings for the cam shaft 18 and incloses the needle and looper actuating cams. From the take-up the thread passes 25 through a guide, thence over an intermittently operating tension device 40 and through suitably located guides, one on the lower part of the slide 22, and thence back underneath the slide and holder 23 to the needle 24. The tension device 40, which is mounted on and moves with the needle bar 30 19, is operated to intermittently grip and release the thread by means of a lever 41, actuated by a cam 42 and held in engagement therewith by a spring 43.

The cam shaft is provided with a belt 40 pulley 44, for connecting it with a motor or drive shaft, and is also provided with a hand wheel 45 for turning it independently of the power connection to adjust the needle and other parts of the machine.

45 The work support and carrier 4, is provided on the outer side with a series of pivoted clamps 46 for holding the work in place thereon. These may be of different widths and variously grouped according to the 50 work to be held in place thereby on the support and carrier 4.

In the present case, the machine as constructed and arranged for sewing reinforcements to glove fingers and thumbs, is provided 55 with a number of wide clamps grouped together for holding separate thumb blanks or pieces, and a number of groups of clamps, each group comprising a wide clamp and two narrower clamps on each side thereof, for holding the finger sections of the hand blanks or pieces, the wide clamp of each group for holding the fore finger section, and the four narrow clamps for holding the second and third 60 finger sections. The clamps may be pivotally 65

mounted on the support or carrier 4 in any suitable way, and are closed to clasp and hold the work against the carrier by springs 47. The clamps may be manually opened and are held open against the pressure of 70 the springs 47 by pivoted dogs or latches 48, engaging with the downwardly extended ends of the clamps below their pivots and formed with outwardly projecting handle arms. As shown, the clamps and dogs may 75 be provided with pivot pins 49 and 50, fitting into horizontal grooves in an outwardly projecting belt 51 on the support and carrier 4, and held in place therein by cap plates 52, fastened to said belt by screws 80 and serving also to confine the springs 47 in place, the belt 51 being slotted vertically to receive the clamps and dogs or latches, and the cap plates 52 being cut away or notched for the handle arms of the dogs 85 or latches to project outwardly between them.

The work support or carrier 4 is provided at the top with a thin steel ring or annular plate 53, opposite the working faces on the 90 upper ends of the clamps. The upper edge of the ring or band 53, which runs below and close to the path of the needle 24, is formed between the clamps 46 with notches, for a purpose hereinafter explained. 95

On the right hand side of the machine, a vertically adjustable incline 54, is carried by a bracket on the ring 3 in the path of the outwardly projecting handle arms of the dogs or latches 48 when they are turned 100 downward into the position shown at the left in Fig. 2, to open the clamps 46, said incline being constructed and arranged to turn the handle arms of the dogs or latches upward into the position shown at the right 105 in Fig. 2, to release the clamps and permit the springs 47 to close them before they reach the stitching mechanism.

On the opposite or left hand side of the machine, a clamp opening roller 55 is 110 mounted on the ring 3, and is shiftable vertically into and out of position to engage with the tail ends of the clamps 46 after they pass the stitching mechanism, and open them, as shown in Fig. 9. The hub of the 115 roller 55 rests on a slotted wedge-shaped or inclined segment 56, which is interposed between it and an outwardly projecting bearing on the ring 3, and through which the pivot stem or journal 57 of the roller passes. 120 This segment is pivoted concentric with the slot therein, on a projection from the ring 3 or roller bearing, and is provided with a handle arm 58 to lift the roller into operative position in the path of the lower ends 125 of the clamps, or lower it into inoperative position.

To coöperate with the clamps 46 in holding the work in place when folded over the ring or band 53 on the upper end or side of 130

the work support or carrier, as shown in Figs. 4, 5 and 6, the support or carrier is provided on the inside adjacent to said ring or band, with points 59, which for the purpose of facilitating their renewal, may be conveniently attached to a band made in sections and removably fitted in an undercut slot in the work support or carrier.

To remove the work from the ring or band 53 and the points 59 after the clamps 46 are opened by the roller 55, a stripping device 60, consisting of a plate formed with vertical and horizontal wings having inclined edges diverging forwardly from a point close to the inner side of the ring or band 53, is carried by an arm 61 extending outwardly over said ring or band, and pivoted to the upper end of a post 62 rising outside of the work support or carrier 4 from the ring 3, as shown in Figs. 1 and 9. The wider part of the lower horizontal wing of the stripping plate is curved downwardly and inwardly, as shown in Figs. 1, 2, 8 and 9, over the points 59, so as to withdraw the work therefrom when it is released by the opening of the clamps 46, and is lifted from the ring or band 53 by the upwardly inclined edge of the upper vertical wing of the stripping plate. The pivoted arm 61 on which the stripping plate is carried, permits it to be turned upwardly out of operative position.

A curved guard wire or rod 63, attached at one end to the post 62, extends therefrom part way around the front side of the work support and carrier, to prevent entanglement of the work with the clamps and springs as it is being placed in position on said support and carrier.

The machine is provided with a trimmer for removing surplus material from and truing the raw edges of the articles or pieces of fabric to be stitched after they are clamped in position on the carrier 4. The trimmer comprises a stationary blade 64, adjustably clamped to a bracket 65 on the case 20, with its cutting edge outside of and adjacent to the upper edge of the ring or band 53, and a movable blade 66, co-operating therewith and adjustably clamped to the front end of a reciprocating bar 67, working in a guide 68, which is pivotally mounted at its rear end upon or concentrically with the cam shaft 18. At its rear end the bar 67 is provided with a roller working in the groove of a cam 69, formed with or attached to the hand wheel 45, or mounted on the shaft 18. The guide 68 is formed with vertically slotted ears, which are connected with one side of the case 20 by screws 70, which permit a limited vertical movement of the guide and of the bar 67 with the movable blade 66. A spring 71, interposed between the guide 68 and an ear or projection on the side of the case 20,

holds the movable blade 66 with a yielding pressure against the stationary blade 64, which works across and close to the upper edge of the ring or band 53. As shown in Figs. 1 and 4, the blade 66 is formed on the side toward the needle with a projection which constantly bears on the upper face of the blade 64 and thus maintains the cutting edges of the blades in proper working relation to each other, the edge of the movable blade being inclined to the edge of the other blade, as shown in Fig. 1, to work with a shearing cut. A flanged deflecting plate 72, attached to the bracket 65, extends therefrom inwardly over the ring or band 53, and underneath the movable blade 66, in position to catch the trimmings cut from the work and conduct them away therefrom.

A chaining point 73, like or similar to those used in overstitch sewing machines, for carrying the stitch formed by the needle 24 and looper 29 across the gaps or spaces between separate pieces or sections of the work, is adjustably supported over and across the needle by a telescoping arm 73', projecting forwardly from the case 20 between the trimmer and needle bar, as shown in Figs. 1 and 11.

An edge lifter 74, attached to the bracket 65 between the deflecting plate 72 and the needle, has an upwardly inclined edge arranged to turn the trimmed edges of the work upwardly and inwardly, and direct them against the inner side of the chaining point 73, by which they will be held in position to be caught by the needle and stitched to the fabric against which they are folded on the ring or band 53.

The machine is provided with a chain cutter for severing the bonds formed by the stitching mechanism between successive pieces or sections of work. It consists as shown in Figs. 1 and 6, of blades 75, fastened to a vertically movable arm 76, with their cutting edges crossing each other in V-shape. The arm 76 is pivoted at its rear end to the front end of a reciprocating bar 77, working in a guide 78 formed on or attached to the case 20. The cutter is retracted by a cam 79, mounted on the shaft 18, and is yieldingly thrust forward over and across the ring or band 53 by a spring 80, which yieldingly holds the rear offset end of the bar 77 with the rear side of said cam, thus avoiding injury to the mechanism in case the cutter in its advance encounters an obstruction on account of misadjustment or failure of the machine to properly function. The arm 76 is formed below the blades 75 with an extension 81, which is pressed by a spring 82 against and lightly rides on the upper edge of the ring or band 53, or the work folded over it and on the upper beveled ends of the clamps 46. The

extension 81, which at the limit of its backward movement by the cam 79 clears the ring or band 53 and the clamps 46, in its advance movement is directed upwardly 5 over the work by the beveled ends of the clamps holding the same, but drops into the spaces between the clamps as they pass, and in its advance movements passes underneath the chains connecting successive pieces 10 of work and through opposite notches in the ring or band 53. The cutter blades 75 are thus lowered into operative position at the proper time to sever the chains linking the pieces or sections of work together. 15 The downward movement of the cutter is limited by the joint between the arm 76 and the bar 77, so that the extension 81 when it drops will pass through the notches in the ring or band 53 without obstruction or interference. 20

For turning the carrier 4 backward, as when the thread breaks, to stitch work which has passed the stitching mechanism, and for turning the carrier forward by 25 hand to facilitate placing a number of pieces of work thereon one after another when the machine is started, a pinion 82 is mounted on the front side of the ring 3 in mesh with the gear or rack 7, as shown in Figs. 1 and 30 3. The pinion stem or shaft 83, which is journaled in the ring 3, is provided at its lower end with a wheel or handle 84, for turning it manually.

The actuating mechanism for operating 35 the needle, looper, trimmer and chain cutter, and for turning the carrier and feeding the work to the stitching mechanism, is preferably located as shown, outside of and at the rear of the carrier 4, so as to leave 40 the space within the carrier entirely open for the work and free from lubricated bearings, contact with which would soil and injure the work, particularly when made of light fabrics of delicate shades.

45 The carrier is formed at its lower end with an inwardly projecting deflecting rim or flange 85, which overhangs the ring 3 and keeps the work hanging therein out of contact with the ring adjacent to the groove or 50 channel in which the tongue 5 on the carrier works, and which has to be lubricated.

As shown in Fig. 5, a grooved plate 86, like or similar to those employed in over-stitch sewing machines, is supported on an 55 arm or bracket of the case 20, outside of the carrier, with the groove in the plate in alignment with the needle 24 with which it cooperates to direct the loops in the thread, formed by the withdrawal of the needle, upwardly into the path of the looper 29, the thread passing to the needle being caught and held by the action of the lever 41 on the tension device 40, while the loops are 60 formed.

65 In the operation of the machine, as the

open clamps 46 pass around the front of the machine in the direction indicated by an arrow on Fig. 1, the operator places the articles, for example blanks for gloves, in position to be sewed on the carrier. The glove 70 blanks, which are cut with thumb and finger extensions for reinforcement of the thumb and finger tips, are folded and placed over the ring or band 3 at the top of the carrier, wrong side out, the end of the reinforcing 75 extension which is to be overstitched to the inside of the thumb or finger section projecting a short distance above the ring or band 53. The clamp 46 is then released by the operator, throwing the handle arm of 80 the associated dog or latch 48 upwardly, as illustrated in Fig. 1, and is closed against the work, as shown in Fig. 4, by the associated spring 47. In placing the work on the carrier, the guard 63 holds depending 85 portions of the work, such as the finger sections of glove blanks, away from the clamps and associated parts of the carrier, enabling the operator to more readily grasp and place them one after another, in position on 90 the carrier. After the clamp is closed, the body or main portion of the blank is folded over the upper edge of the ring or band 53, and caught on the points 59 inside of the carrier. As the work passes the trimmer, 95 the upstanding raw edges, such as the edges at the inner ends of the thumb and finger reinforcing extensions, are cut away approximately even with the folds in the work over the ring 53, as shown in Fig. 4. The 100 trimmings are caught and deflected away from the work by the flanged plate 72.

As the work passes from the trimmer to the stitching mechanism, the trimmed edges, which are apt to be turned down outwardly 105 and left in that position by the trimmer, are turned back upwardly and inwardly and directed inside of the chaining point 73 by the edge lifter 74, as shown in Fig. 10. The chaining point 73, as the work progresses 110 alongside thereof, folds the upstanding trimmed edges inwardly and downwardly upon the folds of the work over the ring 53, as shown in Fig. 5. The work is thus prepared and held in place for stitching, and as it 115 passes the stitching mechanism, the needle 24 co-operating with the looper 29 overstitches the edges of the reinforcements or other parts of the work to the underlying folds thereof over the ring 53. As the gaps or spaces between successive pieces or sections of work 120 pass the stitching mechanism, the chaining point 73 carries the stitch across them, thereby forming bonds between successive pieces of sections. As these bonds pass the 125 reciprocating chain cutter, the extension 81 of the arm 76 drops between the adjacent clamps 46, and is thrust forward through the opposite notch in the ring 53 underneath the chain connecting adjacent pieces 130

or sections of the work, as shown in Fig. 6, the blades 75 being thus carried into operative position to sever the chain or bond.

In case the operator neglects to release 5 the clamps before they pass to the stitching mechanism, the handle arms of the associated dogs or latches 48 will engage with and be turned up by the incline 54, thereby automatically releasing the clamps and permitting them to close before they reach the 10 trimmer and stitching mechanism, and preventing injury to the machine, which would or might result if the clamps were allowed to pass in an open position to the stitching 15 mechanism.

As the work is brought by the carrier opposite the roller 55, the clamps 46 are automatically opened, as shown in Fig. 7, by the engagement of the roller with the lower 20 ends of the clamps, as shown in Fig. 9. When the clamps are opened by the roller 55, the dogs or latches 48 are turned by the preponderating weight of their handle arms into position against shoulders on the 25 clamps, as shown in Fig. 9, to lock and hold the clamps open until they are released either manually by the operator, or automatically by the incline 54, as hereinbefore explained.

30 The work being thus released, is automatically withdrawn from the ring 43 over which it is folded, and from the points 59 on which it is caught, by the stripping device 60, as shown in Fig. 8. When it is released from the carrier, the work falls through or may be caught and conducted away by a delivery device or mechanism (not shown) from the open interior of the carrier, the inwardly projecting rim or 35 flange 85, preventing contact of the work with the ring 3 or that portion of the ring on which the carrier bears, and which is lubricated.

To prevent overthrow of the carrier by 40 the feed mechanism, the machine may be provided with a spring or brake (not shown) bearing against the carrier.

In case the thread which supplies the stitching mechanism is broken, the carrier 45 may be turned backwardly manually, the power drive having been disconnected and the needle rethreaded in order to stitch such parts of the work as have passed the needle, without removing work held on the carrier 50 by clamps which have passed the stripping device 60, by shifting said stripping device and the roller 55 out of operative position until stitched work is brought back by the feed of the carrier to a point opposite or 55 nearly opposite said roller and stripping device.

Various changes in the details of construction and arrangement of parts of the machine to adapt it to work of different kinds, 60 may be made, without departure from the

principle of the invention as defined in the following claims.

I claim:

1. In an overstitch sewing machine the combination with stitching mechanism, of a 70 base ring, an open cylindrical work carrier rotatably mounted on said ring and provided on the outside with clamps and on the inside with points adapted to hold the work folded over the upper edge thereof, 75 means external to the carrier for turning the same and feeding the work thereon to the stitching mechanism and means for automatically closing and opening the clamps before and after they pass the stitching 80 mechanism.

2. In an overstitch sewing machine the combination with stitching mechanism, of a rotary annular work carrier provided with 85 clamps for securing the work in place thereon, means for rotating the work carrier, and means for automatically closing the clamps before they pass the stitching mechanism.

3. In an overstitch sewing machine the combination with stitching mechanism, of a 90 rotary annular work carrier provided with clamps for securing the work in place thereon, means for rotating the work carrier, and means for automatically opening the clamps after they pass the stitching mechanism. 95

4. In an overstitch sewing machine the combination with stitching mechanism, of a rotary annular work carrier provided with 100 clamps for securing the work in place thereon, means for rotating the work carrier, means for automatically closing the clamps before they pass the stitching mechanism, and means for automatically opening the clamps after they pass the stitching mechanism. 105

5. In an overstitch sewing machine the combination with stitching mechanism, of a rotary annular work carrier provided with 110 clamps for securing the work in place thereon, means for rotating the work carrier, means for automatically opening the clamps after they pass the stitching mechanism, and means for manually closing the clamps.

6. In an overstitch sewing machine the combination with stitching mechanism, of a 115 rotary annular work carrier, means for turning the carrier and feeding the work thereon to the stitching mechanism, clamps for holding the work in place on the carrier, means tending to close the clamps, 120 means for locking the clamps open, and means for automatically releasing the locking means and permitting the clamps to close before they pass the stitching mechanism.

7. In an overstitch sewing machine the 125 combination with stitching mechanism, of a rotary annular work carrier, means for turning the carrier and feeding the work thereon to the stitching mechanism, clamps for holding the work in place on the carrier, 130

- means tending to close the clamps, means for automatically opening the clamps after they pass the stitching mechanism, and means for automatically locking the clamps 5 open and for manually releasing them.
8. In an overstitch sewing machine the combination with stitching mechanism, of a rotary annular work carrier, means for turning the carrier and feeding the work 10 thereon to the stitching mechanism, clamps for holding the work in place on the carrier, means tending to close the clamps, means for automatically opening the clamps after they pass the stitching mechanism, means for automatically locking the clamps open, and 15 means for automatically shifting the locking means to release and permit the clamps to close as they pass to the stitching mechanism.
9. In an overstitch sewing machine the combination with stitching mechanism, of a rotary annular work carrier, means for turning said carrier and feeding the work thereon to the stitching mechanism, clamps 20 for holding the work in place on the carrier, means tending to close the clamps, means for automatically opening the clamps after they pass the stitching mechanism, means for automatically locking the clamps in open 25 position when they are automatically opened, and means for automatically shifting the locking means to release the clamps and permit them to close as they pass to the stitching mechanism, said locking means being 30 also manually operable at will to open the clamps and to release and permit them to close.
10. In an overstitch sewing machine the combination with stitching mechanism, of a rotary annular work carrier provided with 35 clamps for securing the work in place thereon, means for rotating the work carrier, and means shiftable into and out of operative position for automatically opening the clamps after they pass the stitching mechanism.
11. In an overstitch sewing machine the combination with stitching mechanism, of a rotary annular work carrier, clamps for 40 securing the work in place thereon, means for automatically turning the carrier and feeding the work thereon to the stitching mechanism, means for automatically opening the clamps after they pass the stitching 45 mechanism, means for manually closing the clamps, and means for manually turning the carrier.
12. In an overstitch sewing machine the combination with stitching mechanism comprising a chaining point for carrying the 50 stitch between successive pieces of work, of a work carrier having a notched edge on which the work is secured, means for actuating the carrier and feeding the work 55 thereon to the stitching mechanism, and means tending to close the clamps, means for automatically opening the clamps after they pass the stitching mechanism, and means for automatically locking the clamps open.
13. In an overstitch sewing machine the combination with stitching mechanism, of a rotary annular work carrier provided with 60 clamps for securing the work folded in place thereon, means for opening the clamps after they pass the stitching mechanism, and a stripping device for removing the work from the carrier after the clamps are opened.
14. In an overstitch sewing machine the combination with stitching mechanism, of a rotary annular work carrier provided with 65 clamps for securing the work folded in place thereon, means for opening the clamps after they pass the stitching mechanism, and a stripping device shiftable into and out of operative position for removing the work 70 from the carrier after it is released by the clamps.
15. In an overstitch sewing machine the combination with stitching mechanism, of a rotary annular work carrier, means for 75 rotating the carrier, clamps pivoted to the outer side of the carrier, springs tending to press and hold the clamps against the carrier, pivoted dogs for opening the clamps, and a stationary incline arranged to 80 turn the dogs into position to release and permit the clamps to close before they pass to the stitching mechanism.
16. In an overstitch sewing machine the combination with stitching mechanism, of a rotary annular work carrier, means for 85 rotating the carrier, clamps pivotally mounted on the carrier, springs tending to close the clamps, a relatively stationary member adapted to open the clamps after 90 they pass the stitching mechanism, and dogs for holding the clamps open.
17. In an overstitch sewing machine the combination with stitching mechanism, of a rotary annular work carrier, means for 95 rotating the carrier, clamps pivotally mounted on the carrier, springs tending to close the clamps, a roller shiftable into and out of operative position and adapted in 100 operative position to open the clamps after they pass the stitching mechanism, and dogs for holding the clamps open.
18. In an overstitch sewing machine the combination of stitching mechanism comprising a chaining point for carrying the 105 stitch between successive pieces of work, of a rotary annular work carrier having a notched rim to which the work is secured, means for turning the carrier, and an upwardly yielding reciprocating cutter limited 110
- 65 120 125 130

in its downward movement and adapted to ride lightly on the notched rim and to drop into operative position and pass through the notches in said rim for severing the 5 bonds formed by the stitching mechanism between successive pieces of work as said notches are brought opposite the cutter.

19. In an overstitch sewing machine the combination with stitching mechanism comprising a chaining point for carrying the 10 stitch between successive pieces of work, of a rotary annular carrier provided with clamps having beveled ends and a rim to which the work is clamped having notches 15 between the clamps, and an upwardly yielding reciprocating chain cutter limited in its downward movement and adapted to ride lightly over the work on the notched rim and over the beveled ends of the clamps,

and to drop into operative position and pass 20 through the notches in the carrier rim as the spaces between the clamps are brought opposite the cutter.

20. In an overstitch sewing machine the combination with stitching mechanism, of 25 a rotary annular work carrier, clamps for securing the work in place thereon, means for turning the carrier and feeding the work thereon to the stitching mechanism, means for automatically opening the clamps 30 and means for removing the work from the carrier shiftable out of and into operative position, and means for manually turning the carrier backward.

In witness whereof I hereto affix my signature. 35

HUMPHREY EVANS.
